UNITED STATES PATENT OFFICE.

AUGUST MATHIS, OF CHICAGO, ILLINOIS.

CENTRIFUGAL FAN.

1,354,673.

Specification of Letters Patent.

Patented Oct. 5, 1920.

Application filed August 7, 1919. Serial No. 315,854.

To all whom it may concern:

Be it known that I, AUGUST MATHIS, a citizen of the United States of America, and a resident of Chicago, in the county of Cook, 5 State of Illinois, have invented certain new and useful Improvements in Centrifugal Fans, of which the following is a specification.

This invention relates to the class of centrifugal air movers or blowers having a blower wheel of the peripherally bladed type, and has for its object:—

To provide a simple and efficient structural formation and association of parts in a blower wheel of the above mentioned type, adapted to afford a strong and substantial connection between the bladed rim portion and the hub portion of the wheel leaving a practically unobstructed central chamber 20 for the incoming air and capable of convenient and effective adjustment to attain perfect concentricity of the wheel rim in relation to the axis of revolution, all as will hereinafter more fully appear. In the 25 accompanying drawings:

Figure 1, is a side elevation with parts broken away and in section of a blower wheel embodying the preferred form of the present invention.

Fig. 2, is a transverse sectional elevation of the same.

Fig. 3, is an enlarged detail sectional elevation of the wheel hub and associated parts.

Fig. 4 is an enlarged detail end elevation of the same.

Fig. 5, is an enlarged detail side elevation of an end portion of the wheel hub.

Fig. 6, is an elevation of one of the spokes 40 of the blower wheel.

Like reference numerals indicate like parts in the several views.

As represented in the drawings the bladed rim member of the blower wheel is 45 formed by a central ring 1 of plate metal, to the respective sides of which the peripheral series of blower blades 2 are secured by the usual flanges and rivets. At their outer ends the blower blades 2 are in turn 50 attached to outer rings 3 of plate metal by flanges and rivets, to maintain the outer ends of the blower blades in proper concentrically spaced relation.

The hub member of the blower wheel 55 comprises annular end portions 4 connected by radial webs 5 with an annular rim por-

tion or shell 6, the respective ends of which overhang the respective webs 5 and are formed with open ended slots 7 for the reception of the ends of the hereinafter described structural metal spokes of the blower wheel.

In the preferred form of the hub, the open ended slots 7 are arranged in pairs tangentially inclined in opposite directions 65 and with one slot of the pair having a greater length than the other, so that the crossed spoke ends of the present structure may pass each other without interference. Inner abutment faces 8 for the attaching nuts of the spokes are formed in right-angle relation to the slots 7 as shown more particularly in Fig. 4.

9 designates disks fitting the annular end portion 4 of the hub aforesaid, and 75 adapted to close the end cavities of the hub formed by the overhanging end portions of the rim or shell 6 and in which the attaching nuts of the wheel spokes are contained.

10 designates the series of spokes connecting the rim and hub members of the wheel together, and which in the present invention are of the V form shown in Figs. 2 and 6, and formed of rod or like structural 85 metal, with the apex of each spoke adapted to engage in a transverse orifice in the central annular ring 1 aforesaid, and with the respective ends of the spoke screw-threaded to receive the attaching nuts 11 by which the spokes are tensioned and adjusted in a convenient and efficient manner to properly center the hub member in relation to the bladed rim member of the blower wheel. 90 With the present construction each V shaped 95 spoke member constitutes two individual spokes of the blower wheel, with the longitudinal spread of said spokes extending to opposite ends of the hub member to provide the required transverse rigidity to the 100 blower wheel in actual use.

In the preferred arrangement of the spokes 10 as shown in the drawings, the same will have the usual tangential and crossed relation, yet any other usual and 105 ordinary arrangement may be employed if found desirable in special uses of the blower wheel.

In all cases the respective forks of each V shape spoke 10 will be on a common plane, 110 so that in the tensioning operation of the nuts 11 an accurate, rapid and effective at-

tainment of the desired balance or centering of the wheel rim with relation to the axis of rotation is secured, without causing distortion or buckling of the rim portion of the 5 wheel.

Having thus fully described my said invention what I claim as new and desire to secure by Letters Patent, is:—

1. In a blower wheel, the combination of a 10 rim member formed by a central ring of plate metal and a peripheral series of attached blower blades, a hub member having overhanging end portions formed with receiving slots, a series of connecting spokes 15 of a V form, the apex of which has engagement in orifices in the aforesaid ring and the inner ends of which spokes pass through the aforesaid slots, and adjusting nuts engaging said inner ends of the spokes and 20 adapted to tension and balance the fan parts, substantially as set forth.
2. In a blower wheel, the combination of a 25 rim member formed by a central ring of plate metal and a peripheral series of attached blower blades, a hub member having overhanging end portions formed with open ended receiving slots, a series of connecting spokes 30 of a V form, the apex of which has engagement in orifices in the aforesaid ring and the inner ends of which spokes pass through the aforesaid slots, and adjusting nuts engaging said inner ends of the spokes and 35 adapted to tension and balance the fan parts, substantially as set forth.
3. In a blower wheel, the combination of a 40 rim member formed by a central ring of plate metal and a peripheral series of attached blower blades, a hub member having overhanging end portions formed with open ended receiving slots having different 45 lengths and oppositely inclined relation, a series of connecting spokes of a V form, the

apex of which has engagement in orifices in the aforesaid ring and the inner ends of which spokes pass through the afore- 45 said slots, and adjusting nuts engaging said inner ends of the spokes and adapted to tension and balance the fan parts, substantially as set forth.

4. In a blower wheel, the combination of a 50 rim member formed by a central ring of plate metal and a peripheral series of attached blower blades, a hub member having overhanging end portions formed with receiving slots, a series of connecting spokes 55 of a V form, the apex of which has engagement in orifices in the aforesaid ring and the inner ends of which spokes pass through the aforesaid slots, adjusting nuts engaging said inner ends of the spokes and adapted 60 to tension and balance the fan parts, and closure plates fitting the ends of the overhanging end portions of the hub member, substantially as set forth.

5. In a blower wheel, the combination of a 65 rim member formed by a central ring of plate metal and a peripheral series of attached blower blades, a hub member having overhanging end portions formed with open ended receiving slots having different 70 lengths and oppositely inclined relation, the inner surfaces of said overhanging portions having abutment faces in right-angle relation to said receiving slots, a series of connecting spokes of a V form, the apex of 75 which has engagement in orifices in the aforesaid ring and the inner ends of which spokes pass through the aforesaid slots, and adjusting nuts engaging said inner ends of the spokes and adapted to tension and bal- 80 ance the fan parts, substantially as set forth.

Signed at Chicago, Illinois, this 5th day of August, 1919.

AUGUST MATHIS.
